W. H. VIBBER

CONDUIT BUSHING WRENCH

Filed Aug. 25, 1926

Inventor.
Wheeler H. Vibber
Egmont Earle & Nichols
Attn.

UNITED STATES PATENT OFFICE.

WHEELER H. VIBBER, OF NEW LONDON, CONNECTICUT.

CONDUIT-BUSHING WRENCH.

Application filed August 25, 1926. Serial No. 131,332.

My invention relates to an improved wrench for applying and removing "conduit-bushings," as the flanged internally-threaded caps extensively used on the conduits of electrical installations are commonly termed, the object being to provide a simple, convenient, time-and-labor-saving tool, whereby such bushings may be readily applied and removed, particularly when located within boxes or cabinets of whatever description and purpose.

With these ends in view, my invention consists in a conduit-bushing wrench having a guide-pin substantially corresponding to the internal diameter of the conduit and provided at its inner end with one or more internally-tapered gripping-fingers extending alongside it and offsetting from it by substantially the thickness of the conduit wall.

My invention further consists in a conduit-bushing wrench characterized as above and having certain other details as will be hereinafter described and particularly pointed out in the claims.

In the accompanying drawings:

Fig. 1 is a view in elevation of one form which my improved conduit-bushing wrench may assume;

Fig. 2 is an underside view thereof;

Fig. 3 is a view thereof in elevation, taken at a right angle to the position in which the wrench is shown in Fig. 1;

Fig. 4 is a view in broken longitudinal section on the line 4—4 of Fig. 1; and

Fig. 5 is a broken view, showing the use of my improved wrench in turning a conduit-bushing located within a box.

In carrying out my invention as herein shown, my improved conduit-bushing wrench is formed with a guide-pin 10 substantially corresponding to the internal diameter of the conduit 11 and therefore to the internal diameter of any standard conduit-bushing, such as the bushing 12. At its inner end or base, the said guide-pin is enlarged, as shown, to form an integral head 13, having two oppositely-located integral gripping-fingers 14 which extend outwardly alongside of the said pin, with the axis whereof their axes are substantially parallel. The inner edges of the said fingers are tapered as at 15 and they are offset from the pin 10 by a space 16 wide enough to permit them to pass over and embrace and grip any standard

bushing, whether the exterior face thereof is 55 ribbed or otherwise roughened or not.

As herein shown, the head 13 is formed with a concentric socket 17 receiving the flattened ball-like terminal 18 of a handle-shank 19 carrying a cross-piece 20 at its outer end, 60 the said terminal 18 being perforated and counterbored at its ends, as at 21, for the reception of a pin 22 in the head 13, whereby a universal joint is formed between the handle-shank 19 and the head 13 forming 65 the wrench proper.

When the wrench is so mounted upon a handle, it becomes easy to use it for applying and removing bushings located within a box or cabinet of any description. In Fig. 5 it is shown as entered into a box 23.

In the practical use of my improved wrench, it is common to slip the bushing over the guide-pin of the wrench and then insert the guide-pin into the conduit into 75 which it is shoved until the bushing is brought into engagement with the threads of the conduit, at which time, if not before, the bushing will be firmly gripped by the fingers of the wrench, which will now be rotated 80 until the bushing has been turned "home." On the other hand, to remove the bushing, the guide-pin is inserted through the bushing into the conduit until the gripping-fingers of the wrench have gripped the bushing with 85 sufficient firmness to permit it to be rotated and so "backed off" the conduit.

My improved wrench will be found of particular convenience in manipulating conduit-bushings within boxes and cabinets, 90 which in many cases are difficult of access on account of the limited room which they offer for the introduction of the hands of the installer.

I claim:

1. A conduit-bushing wrench, comprising a guide-pin provided at its base with an internally-tapered gripping-finger extending forwardly alongside it but offset from it by substantially the thickness of the bushing. 100

2. A conduit-bushing wrench, comprising a guide-pin provided at its base with internally-tapered oppositely-located gripping-fingers extending forwardly alongside it but offset from it by substantially the thickness of the bushing. 105

3. A conduit-bushing wrench, comprising a guide-pin provided at its base with an in-

ternally-tapered gripping-finger extending forwardly alongside it but offset from it by substantially the thickness of the bushing, and a handle having articulated connection with the said wrench.

4. A conduit-bushing wrench, having a guide-pin provided with a pair of tapered gripping-fingers extending forwardly alongside it but separated from it by substantially

the thickness of the bushing, a chambered head for the said pin and fingers, and a handle-shank entered into the chamber of the head and having substantial universal-joint connection therewith.

In testimony whereof, I have signed this 15 specification.

WHEELER H. VIBBER.
